1,992,052

HIGH PRESSURE LUBRICATING DEVICE

Anthony Bizzarri, New York, N. Y.

Application June 17, 1931, Serial No. 544,976

Renewed July 10, 1934

7 Claims. (Cl. 221—47.1)

My present invention relates to lubricating and like pumps, especially those particularly adapted for pumping heavy lubricants, under high pressures, and aims to devise devices of the general character specified which are simple in construction, which may be readily, conveniently and economically fabricated and assembled, and which are highly efficient in operation, the operation of the devices of the present invention in certain of their embodiments being characterized by the ease with which such devices may be loaded with the grease or other lubricant or other substances which are to be pumped by means of such devices, the positive nature of the pumping action, the efficient lubrication of the devices permitting minimizing of clogging, avoiding overheating, stoppages, air pockets and other hindrances and interferences in the operation of the devices of the present invention, the high rate of delivery of the lubricant or equivalent substances rendered possible by the use of the devices of the present invention, and the efficient control and low power conception of the high pressure pumps of the present invention, even in the case of the heaviest lubricant, such as those specifically referred to above. Other objects and advantages of the devices of the present invention, particularly as hereinafter set forth in detail, will in part be pointed out in detail hereinafter and will in part be obvious to those skilled in the art to which the present invention relates.

In the accompanying specification I shall describe, and in the annexed drawing show, an illustrative embodiment of the present invention. It is, however, to be clearly understood that my invention is not limited to the specific embodiment thereof herein shown and described for purposes of illustration only.

Referring to the drawing, the single figure thereof shows, more or less diagrammatically, and partly in longitudinal section and partly in elevation, a high pressure electrically operated pump embodying the principles of the present invention.

Referring to the aforesaid illustrative embodiment of the present invention, and with particular reference to the drawing illustrating the same, 10 indicates a motor or any other driving mechanism embodying the shaft 11 which at its inner 50 end carries the eccentric 12. It may here be stated that any suitable driving means may be employed.

13 indicates the crank or eccentric casing in the form of a casting which contains the various 55 operative parts of the device, except the grease

tank itself which it supports. The crank or eccentric casing 13 serves also as a hollow casing or reservoir for containing the oil or other fluid which serves as a hydraulic fluid in the operation of the device, in a manner which will later be described in this specification. 14 indicates a portion of the casting 13 provided with the annular or other suitable groove 15 on its upper face communicating with certain apertures 16 in the bottom portion 17 of the tank 18 for the heavy or other lubricant which it is the purpose of the electrically or otherwise driven pump of the present invention to feed. The tank 18 embodies the top 19 which includes on the under surface thereof, near the edge thereof, a self-sealing cup 20 made of rubber, leather or other suitable material and which serves, by a sort of plunger-like action, effectively to seal the tank 18 against the re-active pressure brought about by the hydraulic action of the hydraulic fluid in the manner subsequently described. It also serves to retain all of the lubricant within the upper space 21 of the tank 18. The cover 19 and tank 18 is held in place by means of the central bolt 22 which is hollow, as indicated at 23, having the port 24 at the upper end of the hollow rod 22 communicating with the space 21 adjacent the top thereof. The lower end 25 of the hollow rod 22 is threaded so as to fit into the threaded aperture 26 with which the casting portion 14 is provided. At 27 there is provided a flange portion to position the tank by pressure against the bottom 17 thereof, thus to seat the parts properly.

At 28 I have provided the hollow bolt 22 with a flange portion to seat the top 19 of the tank 18 against the side walls of the tank 18. The upper portion 29 of the hollow bolt 22 is threaded to be received within a similarly threaded aperture 31 in the head or boss 30 which is provided with the handles 32 and 33 for manipulating the hollow bolt 22, either to remove the cover in one direction of its operation, or to fasten the cover again in place in the other direction of its operation. It may here be stated that a ring may be used on the under surface of the cover 19 in association with the boss 30 so that when the boss is operated to permit the device to be charged, the cover is removed with the boss, and similarly when the device is to be closed again after it has been charged, the boss carrying the cover 50 may be positioned for sealing the tank again.

The hollow bolt 22, which is fixedly secured in the threaded aperture 26 in the casting portion 14, in the manner already described, carries the follower 34 which is moved upwardly under the 55

action of the hydraulic pressure of the lubricating or other fluid contained in the casting 13 and may be pushed downwardly when the tank is filled again by hand or by the action of a suitable spring

- 5 which will serve to return it to its normal position near the bottom of the tank 18, which spring is not here deemed necessary to be shown. The follower 34 is provided on its under surface with the hollow nipple 35 which has associated therewith 10 the seal 36 in the form of a rubber or leather fitting over the nipple 35 in contact with a portion of the hollow rod 22 beneath the nipple 35. Like the cover 19, the follower 34 is provided with the self-expanding sealing cup 37 which may be made 15 of rubber, leather or other suitable material, and which serves to seal the hydraulic fluid within the lower portion 38 of the tank 19 where the hydraulic fluid is received in the act of discharging lubricant from the upper space 21 in the tank 20 18, which thus prevents the lubricating oil or other fluid from escaping from the space 38 into the space 21 and thus mixing with the lubricant in the upper space 21.

39 indicates a portion of the casting 13 which 25 serves as a cylinder for the pumping mechanism for pumping the lubricating oil or other hydraulic fluid from the reservoir 40 through the delivery pipe 41 through the ports and valve control mechanism subsequently described, into the annular 30 port 15 whence it flows through the inlet port 16 in the bottom 17 of the container 18 and thus into the space 38 for the hydraulic fluid. The cylinder 39 is provided with the intake ports 42 and 43 leading into the cylinder space 44 within 35 which reciprocates the piston 45 under the action of the eccentric 12. The piston 45 is preferably hollow and may contain within it the compression spring 46, the upper end of which bears against the inner face of the end 47 of the piston 40 45, while the lower end of which bears against the inner face 48 of the sealing nut 49 which serves to close the aperture 50 with which the outer portion 51 of the casting 13 is provided. In the portion 52 of the casting 13 I provide a 45 check valve 53 positioned by means of the spring 54 so as to control the port 55 adjacent the bottom of the cylinder space 44, 56 indicating a by-pass port also provided adjacent the bottom of the cylinder space 44 for a purpose to be described 50 in substantial detail later in this specification.

The ball valve 53 and the spring 54 are positioned in the substantially cylindrical space 57 which is closed by the sealing nut 58 in the manner made clear in the drawing. The cylindrical space 57 communicates with the space 59 in the bend 60 of the delivery conduit 41 already referred to. At its other end, the delivery conduit 41 includes the bend 61 provided with the threaded nipple 62 communicating with the port 63 in the portion 64 of the casting 13. The portion 64 of the casting 13 just referred to embodies a petcock 65 operated by means of the handle 66 and embodying therein the substantially L-shaped port or passageway 67 so that when the pet-cock is in one position, such as that shown in the drawing, the hollow of the tube 41 will by means of the L-shaped port 67 and the port 68 of the casting portion 14 communicate with the annular port 15 in such casting portion 14 and thus, therefore, the inlet ports 16—16 with the lower interior portion 38 of the tank 18. The position just referred to corresponds to the charging of hydraulic fluid under pressure into the lower portion 38 of the tank 18 and thus to the discharge of lubricant.

cant under pressure from the upper portion 21 of the tank 18.

In the other position of the pet-cock 65, the L-shaped port 67 will bring the port 68 in the casing portion 14 in communication by means of the annular port 15 with the inlet port 16—16 and thus with the interior portion 38 of the tank 18, into communication with the discharge port 69 which will serve to restore hydraulic fluid to the reservoir space 40 through the discharge port 70 into the upper space 71 of the reservoir and thus into the lower space 40 thereof where the supply of hydraulic fluid, such as lubricating oil or the like, is maintained.

The by-pass port 56 communicates with the 15 interior substantially cylindrical space 72 in the casting portion 73 which is sealed at its open end 74 by means of the adjusting screw 75 having the knurled head 76 by means of which it may be operated. The adjusting screw serves to ad- 20 just the tension of the compression spring 77 within the cylindrical space 72, such compression spring 77 acting against the ball valve 78 which serves as a check valve controlling the by-pass port 56. 25

The purpose of the by-pass port 56 and its associated adjustable valve mechanism is to permit the by-passing of hydraulic fluid when the pressure in the reservoir 40 exceeds the pressure for which the spring 77 is set by the adjustment 30 of the screw 75. The hydraulic fluid thus bypassed through the by-pass port 56 and past the valve mechanism referred to passes through the by-pass conduit 79 through the bend 80 through the threaded nipple 81 into the cylindrical space 35 32 provided within the casting portion 83 which contains the mechanism for pumping the lubricant from the upper space 21 in the tank 18, thereby the hydraulic fluid in the form of lubricating oil serves to lubricate the operative portions of 40 the grease-pumping mechanism contained in the cylindrical space 82. The excess of hydraulic fluid in the form of lubricating oil passes through the port 84 and thence into the reservoir 40 where the lubricating oil or equivalent hydraulic fluid is 45 stored.

The casting portion 83 comprises a cylinder which, as already indicated, contains the pump mechanism for pumping the grease from the upper space 21 in the tank 18. The casting portion 83 is provided with the stepped portion 85 below which the diameter of the cylinder is less than it is above the stepped portion 85, the cylindrical space above the stepped portion 85 being designated by reference character 86. 50 55

Within the cylindrical space 32 below the stepped portion 85 which carries a washer 87 which in turn carries a leather sealing cup 88 is the compression spring 89 resting on the spring retainer 90 held in position by a pin (not shown) 60 passing through the plunger 92.

The plunger 92 reciprocates within a casing 93, the lower portion 94 of which is of reduced diameter and the upper portion 95 of enlarged **external** diameter. The upper portion 95 of enlarged external diameter is in the form of a cup, the upper portion 96 of which in the form of a tapered flange rests in the correspondingly tapered seat 97 with which the interior of the casting portion 98 is provided. 99 designates a steel bushing which fits into the portion 96 of the cylinder 93 and which supports the check valve mechanism shortly to be described. 65 70

f The check valve mechanism which is contained within the hollow lock nut 100 which contains 75

the groove 101 by means of which the hollow lock nut 100 may be manipulated is provided with the internal space 102 which contains the compression spring 103 and the check ball valve 104 which guards the port 105 through which grease from the upper space 21 of the tank 18 is discharged through the ports 106 with which the reduced lower portion 107 of the hollow lock nut 100 is provided. While four such discharge ports 106 have here been shown, their number may be varied as desired. From the hollow ports 106 with which the lower portion of reduced diameter 107 of the hollow lock nut 100 is provided, the grease or equivalent lubricant passes through the discharge outlet 108 through the threaded nipple 109 into the hose or other suitable conduit 110 from which it is discharged at the end 111 which may, if desired, carry the bayonet or other suitable coupling 112.

The piston 92 has the lower end thereof in the piston cup 113, the lower face of the piston cup 113 being maintained by the plunger 92 under the action of the spring 89 bearing against the spring retaining member 90, against the operative face of the eccentric 12 so that, as the eccentric 12 rotates under the propulsion of the electric motor 10 or other suitable driving mechanism, the plunger 92 and the piston cup 113 will constantly be maintained against the operative surface of the eccentric 12 and thus operated thereby, except when the cam mechanism shortly to be described maintains the piston cup 113 and thus the plunger 92 out of operative contact with the eccentric 12. It may be stated that under normal conditions, the plunger 45 is kept constantly in action, thus serving to maintain hydraulic fluid constantly available for immediate operation and also to lubricate constantly the lower portion of the plunger 92, while the piston cup 113 of the plunger 92 in engagement with the inner surface thereof is not in action except when, by operation of the cam mechanism subsequently describe, it is desired to put the same into action.

The various parts of the grease-pumping mechanism described above are maintained in proper assembled relation by means of the hollow lock nut 100 already described, which is suitably threaded into the casting portion 98 and thus keeps the various parts of the grease-pumping mechanism in proper assembled operative relation. I prefer, however, to provide the hollow sealing nut or cap screw 114, which is threaded over the upper externally threaded portion of the hollow lock nut 100, thus completing the assembly of the grease-pumping mechanism.

115 indicates a port which communicates by way of the hollow portion 23 of the hollow nut 22 and the outlet port 24 communicating with the interior portion 21 of the tank 18 to permit the discharge of heavy grease or other lubricant under the action of the hydraulic fluid in the lower space 38 of the tank 18, thence through the port 115 into the cylindrical space 86 and thence under the action of the plunger 92 into the space 102 immediately below the check valve mechanism past which it goes through the outlet ports 106 through the discharge port 108 through the nipple 109, thus into the conduit 110 from which it escapes through the end 111 past the coupling 112. It may here be stated that the passage of the grease past the upper end of the plunger 92 into the space 102 may be effected by means of the ports 116 of which any desired number may

be provided, here shown as four, in the upper portion of the casing 95.

The operation of the device may be controlled by any suitable means, such as the means illustrated in the drawing and comprising, for example, the cam 117 held by the pins 118 and 119 which are secured in any suitable portion of the casting 13. The cam 117 is in turn pivoted by means of the pin 120 to the rod 121 which slides in an open or other suitable bearing 122 with which the casting 13 may be provided. On the inner face of the casting surrounding the rod 121 is a compression spring 123 held by the pin 124 passing through the rod 121, the spring 123 being thus held in position between the inner surface of the casting 13 around the rod 121 and the pin 124. Normally, under the action of the spring 123 the cam 117 will be pushed forwardly to the right in the single figure of the drawing and the end 117' of the cam 117 will engage the under surface of the piston cup 113, thus to disengage the cup 113 and the plunger mounted within the same from the eccentric 12 which will thus no longer be effective to operate the grease pumping mechanism. It will be noted that the cam 117 by means of the elongated slot 118 with which it is provided and the similarly elongated opening 119' which is provided, around the pins 118 and 119, respectively, serves as a sort of lever which goes forward and then drops to a position which will render effective its action to disengage the piston cup 113 from the operative surface of the eccentric 12 by providing a space between the lower surface of the cup 113 and the surface of the eccentric 12.

In order to operate the grease-pumping mechanism I provide means for counteracting the effect of the spring 123 which would serve normally to maintain the grease-pumping mechanism in inoperative position. For this purpose, I may provide the Bowden cable or other suitable pulling cable 125, provided with the outer casing 126, one end of the cable 125 being attached to the end 127 of a bell crank lever having the shorter end 128 and being pivoted at 129 to the hose 110, the longer end 130 of the bell crank lever serving as a handle which may be manipulated by the operator when he seizes the operative end of the discharge pipe or hose 110 to pull on the cable 125, the other end of the cable 126 being secured to the outer end of the rod 121, the cable being threaded through a bracket 131 with which the casting 13 may be provided.

This completes the description of the construction of the aforesaid illustrative embodiment of the present invention. The manner of assembling the device will, it is believed, clearly appear from the foregoing description but may be briefly summarized as follows: The casting 13 being in the form specified, the sealing members 58, 75, 49 and 114 being assumed to be not applied, the pet-cock 65 may be inserted in the usual way and thereafter the grease or lubricating tank 18 may be applied by the application of the tank proper, the insertion of the hollow bolt 22, the application of the cover 19 and the boss 28, the follower 34 having previously been inserted about the hollow bolt 22.

The eccentric 12 having been applied in any suitable way to the shaft 11, the various parts of the hydraulic pump embodying the plunger 45 and the spring 46 may be applied and then the sealing member 49 applied to close the hydraulic fluid pumping mechanism. After this, the check valves 53 and 56 and their associated

springs may be put in place in the casting portions 52 and 73 and the sealing members 58 and 75 then screwed into place to seal the respective check valves.

5 The various operative parts of the grease pump, including the plunger 92, the plunger or piston cup 113, the surrounding sleeve 93, the steel bushing 99, the check valve 104 with the associated spring 103 and the associated parts, 10 are inserted in the casting portion 98, after which the cap 114 may be screwed into place. The various nipple connections 62, 81 and 109 may be secured and the associated parts positioned in a manner which will readily be apparent to those 15 skilled in the art to which the present invention relates, thus completing the assembly of the device.

The mode of operation of the device illustrated in the foregoing drawing and described in the 20 foregoing specification will, it is believed, clearly appear from the foregoing specification and drawing but may be briefly summarized as follows:

In operating the device, the operator may proceed substantially as follows: In order to fill, 25 charge or service the device, the boss 28 is unscrewed from the threaded upper end 29 of the hollow bolt 22, after which the cover 19 carrying the sealing cup 20 may be removed. With 30 the tank 18 discharged of lubricant, the follower 34 may be pushed down in the tank, the pet-cock 65 being moved from the position shown in the single figure of the drawing into a position which will connect port 68 with port 69, thus 35 permitting the hydraulic fluid in the nature of lubricating oil in the lower compartment 38 of the tank 18 to be discharged into the reservoir 40.

The depression of the follower 34 may be effected 40 by filling the upper space 21 of the tank 18 with the heavy or other lubricating grease to be used. At this time the valve 65 is positioned so as to connect the passage 68 with the passage 69, thus permitting the fluid in the lower portion 45 of the tank 18 to flow into the reservoir 40. When this operation is completed, the valve 65 should be returned to its position connecting the 50 passages 63 and 68. Assuming, now, that the motor 10 is started, causing the shaft 11 carrying the eccentric 12 to rotate, and assuming also that the operator has not operated the bell crank 55 lever 130 to bring the cam 117 into the position which it occupies in the single figure of the drawing, the grease plunger 92 and the plunger cup 113 associated therewith will be kept out of operative contact with the eccentric 12 by the action of the cam 117. The plunger 45, on the other hand, will have the end 47 thereof in operative contact with the eccentric 12 by means of the 60 spring 46 for that purpose. Hydraulic fluid, for example, lubricating oil, from the reservoir 40 will thus be pumped by the plunger 45 past the check valve 53 into the elbow 60 through the conduit 41, the nipple 62, into the L-shaped port 67 of the pet-cock 65, and thence through the 65 port 68 into the annular channel 15 through the ports 16-16 into the space 38 in the lower portion of the tank 18 beneath the follower 34. The pressure of the hydraulic fluid will not, however, 70 without the operation of the grease pump embodying the plunger 92, be sufficient to lift the follower and to force the hard grease or other lubricant out of the space 21 in the tank 18. Accordingly, when the pressure for which the bypass valve embodying the check valve 73 has

been set is exceeded, lubricating oil will be forced into the conduit 79 through the nipple 80 into the space 32 to lubricate the lower portion of the plunger 92 and to pass through the port 84 back into the reservoir 40. After all the grease has 5 been ejected from the tank 18, and to remove the pressure of the oil from the tank 18, the pet-cock 64 is turned by means of its handle 66 so that the L-shaped portion 67 now connects passages 68 and 69, thus permitting the oil to run back into 10 the reservoir.

However, as soon as the operator manipulates the bell crank lever 130 to move the cam 117 into the position shown in the single figure of the drawing, the plunger cup 113, and thus the plunger 92 within the same, will be brought into operative contact with the eccentric 12, thus to put the grease pump into operation and, with the assistance of the hydraulic fluid acting beneath the follower 34 in the space 38 in the lower portion of the tank 18, to force grease under high pressure through the nipple 109, the hose 110, to the outlet 111 supplied with the bayonet or other connection 112.

This operation may continue any number of 25 times until the tank 18 is exhausted. It may here be stated that when the tank is completely exhausted, and it is desired to recharge the same, the pet-cock 65 is moved from the position shown in the single figure of the drawing, which corresponds to the position in which heavy grease or lubricant will be discharged from the upper compartment 21 of the container 18, to a position at right angles in which the hydraulic fluid in the form of lubricating oil in the compartment 38 30 beneath the follower 34 will be passed from such compartment through the port 68, the L-shaped port 67, port 69 back into the reservoir 40. At the same time the tank 18 can be recharged by putting heavy grease or other lubricant in the 40 upper compartment 21 above the follower 34, thus preparing the device for the further discharge of grease or other lubricant.

This completes the description of the mode of operation of the aforesaid illustrative embodiment of the present invention. It will be noted that the device is simple in construction, may be conveniently fabricated and assembled, and is highly efficient in operation. By means of the devices of the present invention highly difficult 50 and heavy lubricants may be pumped under high pressure and with a very satisfactory rate of feed. The device itself is further characterized by its substantial freedom from clogging, overheating, stoppages, air pockets and other defects which would hinder its efficient operation, while permitting a high rate of delivery with low power consumption and efficient control of the lubricating operation.

Other superiorities and advantages of the 80 devices of the present invention, particularly as exemplified in the foregoing illustrative embodiment of the same, will readily occur to those skilled in the art to which the present invention relates.

What I claim as my invention is:

1. In a device for pumping lubricant, a container providing a source of supply of lubricant, outlet means communicating with said source of supply within said container, a separating member within said container on one side of which lies said source of supply of lubricant, and means comprising a source of supply of lubricating hydraulic fluid communicating with said container on the other side of said separating member for 70 75 85 90 95 100

pressure-applying means in continuous operation, in combination with auxiliary pumping mechanism for pumping the lubricant being discharged from said container by the hydraulic pressure applied thereto by the movement of said separating member in said container, means for utilizing a portion at least of said lubricating fluid

for lubricating a portion at least of said auxiliary pumping mechanism, and manually controlled means associated with said motor-operated means for controlling said auxiliary pumping mechanism upon the actuation of said manually controlled means. 5

ANTHONY BIZZARRI.
